[57] CLAIM

The ornamental design for a tie-down belt rewind crank, as shown and described.

DESCRIPTION

FIG. 1 is a perspective view of a tie-down belt rewind crank showing a first embodiment of my new design with the broken line showing of partial structure and a rewind belt being for illustrative purposes only and forming no part of the claimed design.

FIG. 2 is a side elevation view of said first embodiment thereof;

FIG. 3 is a top plan view of said first embodiment thereof;

FIG. 4 is a side elevation view of a tie-down belt rewind crank showing a second embodiment of my new design;

FIG. 5 is a top plan view of said second embodiment thereof;

FIG. 6 is an enlarged end elevation view of said second embodiment thereof;
